US00D841595S

(12) **United States Design Patent** (10) **Patent No.:** **US D841,595 S**
(45) **Date of Patent:** **** Feb. 26, 2019**

(54) **CONNECTOR**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/642,630**

(22) Filed: **Mar. 30, 2018**

Related U.S. Application Data

(63) Continuation of application No. 29/558,758, filed on Mar. 21, 2016, now Pat. No. Des. 814,422, which is (Continued)

(57) **CLAIM**

The ornamental design for a connector, as shown and described.

DESCRIPTION

FIG. 1 is a bottom front perspective view of a connector showing the claimed design;
FIG. 2 is a front view thereof;
FIG. 3 is a rear view thereof;
FIG. 4 is a side view thereof;
FIG. 5 is another side view thereof;
FIG. 6 is a top view thereof; and,
FIG. 7 is a bottom view thereof.

The dashed broken lines in the figures show portions of the connector that form no part of the claimed design.

The dot-dash broken lines in the figures and the area within the dot-dash broken lines show portions of the connector that form no part of the claimed design.

1 Claim, 4 Drawing Sheets

Related U.S. Application Data

a continuation of application No. 29/529,183, filed on Jun. 4, 2015, now Pat. No. Des. 751,991, which is a continuation of application No. 29/449,244, filed on Mar. 14, 2013, now Pat. No. Des. 731,434, which is a continuation-in-part of application No. 29/432,034, filed on Sep. 12, 2012, and a continuation of application No. 29/426,587, filed on Jul. 6, 2012, now Pat. No. Des. 684,539.
